CLAIM

I claim the ornamental design for the cord management system, as shown and described.

DESCRIPTION

FIG. 1 is a perspective view of a cord management system according to a first embodiment of my new design.

FIG. 2 is a rear view of the cord management system of FIG. 1.

FIG. 3 is a left view of the cord management system of FIG. 1. The right view is a mirror image of the left view.

FIG. 4 is a front view of the cord management system of FIG. 1.

FIG. 5 is a bottom view of the cord management system of FIG. 1.

FIG. 6 is a front view of the cord management system of FIG. 1 including a structure drawn in broken line showing the claimed design in a position of use. The broken line structure forms no part of the claimed design.

FIG. 7 is a right view of the cord management system of FIG. 1 including a structure drawn in broken line showing the claimed design in a position of use. The broken line structure forms no part of the claimed design.

FIG. 8 is a perspective view of a cord management system according to a second embodiment of my new design, which represents a change in the orientation of the arms of the figure.

FIG. 9 is a rear view of the cord management system of FIG. 8.

FIG. 10 is a left view of the cord management system of FIG. 8. The right view is a mirror image of the left view.

FIG. 11 is a front view of the cord management system of FIG. 8; and,

FIG. 12 is a bottom view of the cord management system of FIG. 8.
